UNITED STATES PATENT OFFICE.

HUGO GROMMANN, OF SCHOENHEIDE, GERMANY, ASSIGNOR TO CARL EDUARD FLEMMING, OF SAME PLACE.

WORK-HOLDER FOR BRUSH-MACHINES.

SPECIFICATION forming part of Letters Patent No. 603,187, dated April 26, 1898.

Application filed December 10, 1896. Serial No. 615,225. (No model.) Patented in England August 7, 1896, No. 17,491, and in Luxemburg August 8, 1896, No. 2,585.

To all whom it may concern:

Be it known that I, HUGO GROMMANN, a subject of the King of Saxony, residing at Schoenheide, Kingdom of Saxony, German Empire, 5 have invented an Improvement in Work-Holders for Drilling Brush-Backs, (patented in England, No. 17,491, dated August 7, 1896, and in Luxemburg, No. 2,585, dated August 8, 1896,) of which the following is a specification.

My invention relates to machines for drilling brush-boards and binding the bristles in the holes drilled therein; and it consists in the special features of construction and arrangement hereinafter fully shown and described.

In the drawings, Figure 1 is a side view of the machine; Fig. 2, a top view of the lower or table portion of the machine. Fig. 3 is a 20 front view of Fig. 2. Fig. 4 is a detail side view of a work-table and its attached mechanism. Fig. 4^a is a detail sectional view on line 4^a 4^a of Fig. 4. Figs. 5, 6, and 7 are views of details of the supporting means for the 25 work-tables. Fig. 8 is a side view of the grooved driving-disk. Fig. 9 is an edge view of the same with its attached mechanism; Fig. 10, a plan view of the same. Fig. 11 is a side view showing a modification of the 30 driving mechanism. Fig. 12 is an end view thereof, and Fig. 13 is a plan view of this modification.

The work-tables *a* are similarly screwed to their supporting-brackets *b*, one of said tables 35 being intended to hold the brush-board in which holes are to be drilled. The other holds the board in which the brush-bristles are to be inserted. The vertical arms *c* of the brackets move through guides *d*, which are 40 pivoted to a main block or guide-standard *f* by the screw *e*, Figs. 2, 3, and 4, and from this construction the work-table *a* may have vertical movement through the guides *d* and a tilting movement from the screw *e* as a center. The lower ends of the bracket-arms *c* 45 carry bolts *g*, the inner ends *h* of which have antifriction-rollers, which slide in the slots *k* of the plates *i*, which are screwed to the guide-block *f*. This plate *i* may be removed and 50 replaced by another plate having a different form of slot, whereby a brush-board of any

desired form may be operated upon, and its surface will by the appropriate slotted plate be caused to move in proper proximity to the tool. The plates *i* are of the same shape as 55 to their slots for both tables, as of course the same block is removed from one table and placed upon another.

The guide block or standard *f* is adapted to slide in a block *m*, which may turn about 60 a pin *l* in the plate *r*, and thus swing the guide, with the work-table, laterally. The lower end *fⁿ* of this guide-block *f* has a roller *o*, entering a slot *q* in a plate *p*, which is also removable and may be replaced by another 65 plate having a differently-shaped slot, so as to give the work-table any desired lateral movement to suit the longitudinal surface form of the brush-board. The plates *p* are secured to the cross-plate *r*, which is vertically adjustable on the frame *s* and adapted to be held by the screws *S*. An adjusting-screw *S'*, Fig. 3, engages the plate *r*, and by this arrangement the work-tables may be adjusted to suit different thicknesses of boards, 70 both tables being adjusted simultaneously 75 through their standards *f* from the cross-plate *r*.

The automatic movements of the work-tables and the main standards are effected as 80 follows: A piece *2* is fitted to the standard *f* below the work-table to slide from front to rear, a pivot-pin *3* passing through the sliding piece and having a nut *4* to hold the sliding piece on the pin. A block *6*, Figs. 5, 6, 85 and 7, is carried pivotally by a pin extending between the upper parts of the piece *2*. A second block *6¹* is arranged above the block *6*, said block *6¹* being carried on a pin extending between the sides of the standard *f*. 90 Over the blocks *6* and *6¹* a sliding block *6^a* is placed, the forks of which embrace the blocks, while the sole portion *6^b* is screwed to the work-table. The rear end of the pin *3* fits tightly into a plate *g'*, adapted to slide vertically on a bracket *w*, which is carried by a slide *d^x*, movable transversely of the machine or in the direction of the longer dimension of the brush-board, while a lower slide *d^y*, which carries the upper slide *d^x*, moves in the direction of the width of the brush-board. 95 The upper slide *d^x* has a rack *z* on its lower 100

side engaging a pinion z' on a shaft u , supported in bearings u' of the frame s , Fig. 2. The shaft u carries at its rear end a pinion z^2 , engaged by a vertically-sliding rack y , Figs. 5, 2, 9, and 10, having a roller y' extending into a groove in the face of a disk t . This disk is rotated step by step by a pawl t' engaging the teeth of the disk, the said pawl being carried by a block t'' , which moves in a way in a standard t''' , the block, being connected with a pitman t^5 , thus imparts motion to the rack y and thence to the pinion z^2 and the shaft u , which operates the slide d^x , and with it the table a , which is thus moved in the direction 15 of the length of the brush-board, this movement being permitted by the swinging of the support or standard f . The movement in the forward and backward direction of the work-table or in the direction of the width of the 20 brush-board is performed by the movement of the slide d^3 , which is effected from a second groove in the disk t , (see full lines in Fig. 8,) into which a roller y^2 extends, this roller being carried by a sliding piece v , moving in 25 a slotted frame and being fixed to the end of the rod x , the other end of which is connected to the slide d^3 . A spring-box f^4 is fixed to the cover of the pivoted guide-block m , the spring-bolt of said box being arranged to 30 press upon the standard f , and thus force the same upwardly to relieve the frictional contact between the pivot of the standard and the walls of the slot q .

The means for operating the drills and the 35 binding device for the bristles form no part of my invention and are not described herein.

Figs. 11, 12, and 13 show a modification of the machine whereby the amount of movement of the work-tables may be varied both 40 lengthwise and laterally. The rack y in this modification, which is driven by the grooved disk t , drives the pinion z^2 on the shaft u^4 , Fig. 13, which shaft is supported in bearings $t^x l^1$. The pinion z^2 engages the gear T on a shaft 45 B , which is adjustably held in a slot of the frame S^1 , said slot being concentric to the shaft u^4 . Gear T drives the shaft u^3 through an exchangeable gear z^3 thereon, which shaft also carries a gear z^5 , driving the gear z^4 on 50 the shaft u . This shaft in the main form carries the gear z' , which moves the work-table transversely of the machine. As the gear z^3 is exchangeable, the movement of the slide d^x may be varied to change the length of movement of the work-table. The motion of the 55 lower slide d^3 crosswise of the brush-board to move the table forward and backward longitudinally of the machine is also effected by the disk t , which, through the slide v and rod x , is 60 connected with a swinging lever K by a pin r' and slot, the end of the rod working in a bearing u^5 . This lever is connected with the lower slide d^3 by a rod connected at $b^2 b^3$ to the slide and lever, respectively, and the fulcrum b^4 of 65 the lever is adjustable in a loop k^1 , so that the length of the lever-arm may be changed.

The machine is driven by a crank t^0 through

a pinion t^{11} and a gear t^{12} , as shown in Figs. 1, 2, 8, and 12, the latter gear being on the shaft of the disk t .

I claim—

1. In combination the frame, the standard f having a forked upper end, the transverse slide, the pin 3 and block 2 forming the connection between the slide and the upper forked end of the standard, the work-table, the forked block 6^c depending therefrom into the forked end of the standard and engaging a portion of the block 2 , the brackets b depending from the work-table alongside the standard, the slotted guides engaging the said brackets, the pivoted guide-block, the slotted guide for the standard f , and a second slide carrying the transverse slide with means for operating said slides, substantially as described.

2. In combination the work-table, the swinging standard, the connection between the standard and table comprising the sliding block 2 in the standard, the table pivotally connected to the standard and engaging the block, the pin 3 engaging the block 2 and means for moving the pin longitudinally and laterally, substantially as described.

3. In combination, the standard carrying the work-table, the sliding and pivotal connection m for the standard to allow it to have vertical movement as it swings, the slotted guide-plate receiving a roller from the standard, and a vertically-adjustable support for the slotted guide-plate, said adjustable support carrying also the pivotal connection m , substantially as described.

4. In combination the work-table, the standard f carrying the same, the pivoted guide-block m through which the standard may slide, the slotted guide to cause the standard to have vertical sliding movement as it swings, and the spring-box having a bolt for pressing the standard upwardly to relieve pressure on the slotted guide-plate, the said spring-box being suspended from the pivoted guide-block to oscillate with the standard, substantially as described.

5. In combination the pivoted work-table, the pivoted standard carrying the same, the slides d^x , and d^3 , for moving the said parts on their pivots, the grooved disk t , the gearing operated thereby and connected to the slide d^4 , for operating the same, said gearing comprising an exchangeable portion, and the connections from the disk to the slide d^3 , comprising an adjustable lever whereby the traverse of the slides may be changed to suit different brush-boards, substantially as described.

In testimony whereof I have hereunto set my hand, at Schoenheide, this 25th day of August, 1896, in the presence of two subscribing witnesses.

HUGO GROMMANN.
